(57) **CLAIM**

The ornamental design for a case for a solid shampoo as shown and described.

DESCRIPTION

1. Case for a solid shampoo

FIG. 1.1 is a perspective view of a case for a solid shampoo according to the present design;

FIG. 1.2 is another perspective view thereof;

FIG. 1.3 is a front elevation view thereof;

FIG. 1.4 is a rear elevation view thereof;

FIG. 1.5 is a left side view thereof;

FIG. 1.6 is a right side view thereof;

FIG. 1.7 is a top plan view thereof;

FIG. 1.8 is a bottom plan view thereof;

FIG. 1.9 is a perspective view thereof, shown with the lid opened; and

FIG. 1.10 is a perspective view thereof, shown with the lid opened and the handle turned.

(Continued)

The present design relates to a case for a solid shampoo. The broken lines depict portions of the article that form no part of the claimed design.

1 Claim, 10 Drawing Sheets
